(57) **CLAIM**

The ornamental design for a lamp, as shown and described.

DESCRIPTION

FIG. 1 is a bottom left perspective view of a lamp showing my new design;

FIG. 2 is a left side elevation view thereof, the right side elevation view being a mirror image;

FIG. 3 is a front elevation view thereof, the rear elevation view being a mirror image;

FIG. 4 is a bottom plan view thereof;

FIG. 5 is an enlarged fragment of a portion of the lamp shown in FIG. 1 and labelled 5;

FIG. 6 is an enlarged fragment of a portion of the lamp shown in FIG. 2 and labelled 6; and,

FIG. 7 is an enlarged fragment of a portion of the lamp shown in FIG. 4 and labelled 7.

FIGS. 1–4 include break lines, where the break lines in the vertical stems of the lamp are understood to represent uniform breaks for all vertical stems, and those portions of the article between the break lines form no part of the claimed design. The broken lines represent environmental subject matter and form no part of the claimed design. The short-long lines show boundaries of the enlarged portions of the claimed design and form no part of the claimed design.
